UNITED STATES PATENT OFFICE.

HUGO GOLDSMITH, OF CINCINNATI, OHIO, ASSIGNOR, BY MESNE ASSIGNMENTS, TO
THE P. GOLDSMITH SONS COMPANY, OF CINCINNATI, OHIO, A CORPORATION OF
OHIO.

ATHLETIC PROTECTIVE PAD.

Application filed March 25, 1922. Serial No. 546,821.

To all whom it may concern:

Be it known that I, HUGO GOLDSMITH, a citizen of the United States of America, and a resident of Cincinnati, in the county 5 of Hamilton and State of Ohio, have invented a new and useful Improvement in an Athletic Protective Pad, of which the following is a specification.

My invention relates to a combined thigh 10 and knee guard such as is used by football players, soccer, hockey and other sports requiring protectors.

An object of my invention is to provide a simple structure which will afford the 15 maximum of protection to the wearer.

Another object of my invention is to provide a device of the class described, which will require a minimum of labor and effort to produce.

These and other objects are obtained by 20 means described herein and disclosed in the accompanying drawings, in which:—

Fig. 1, is a fragmental front elevation of a pair of football pants having mounted 25 upon them a protector embodying my invention.

Fig. 2, is an enlarged development of a protector embodying my invention.

Fig. 3, is an enlarged sectional view on 30 line 3—3 of Fig. 2.

Fig. 4, is a view taken on line 4—4 of Fig. 3, showing the parts in the positions assumed when applied to a wearer.

Fig. 5, is a sectional view taken upon line 35 5—5 of Fig. 1.

The protector of my invention comprises a single flexible sheet 5, of preferably a very soft leather, the inner side of which is covered with and has mounted upon it, a suitable padding material 6, such as wool, wool 40 fiber, felt or the like. The upper portion of the sheet 5, is developed into a thigh guard, and carries upon its outer side, a number of pockets which may be provided 45 in any suitable manner, such as by securing a sheet of fabric 7, upon the sheet 5, and providing rows of stitching extending in substantial parallelism lengthwise of the sheet 5. Within the pockets formed in this 50 manner, are disposed reinforcing strips 8, which may be curved fiber strips. Disposed upon the outer side of the sheet 5, at the lower end thereof, is a large resilient pad 9, preferably of sponge rubber, which may 55 be secured upon sheet 5, in any suitable

manner, such as by being sewed thereto as shown at 10. The pad 9, is disposed in such position that it will take a position immediately above and in front of the knee of the wearer, of the device. Suitable eyelets 60 11, are provided in the protector and in the pair of pants 12, whereby the protector may be removably mounted upon the pants. When mounted upon a wearer, the pad 6, is disposed between the wearer and the 65 sheet 5.

At the upper edges of the pants, adjacent to the thigh portions thereof, pockets 13 are formed, in each of which is located a rubber sponge pad 14. The rubber pad and 70 its pocket are located between the material of the pants and the felt pad 16.

What I claim is:—

1. In a device of the class described the combination of a flexible sheet, padding 75 mounted over one side thereof, vertical curved reinforcing strips mounted upon the opposite side thereof and extending over substantially one half of said last mentioned side, and a resilient shock absorbing 80 pad mounted on the second half of the second mentioned side of the sheet.

2. In a device of the class described the combination of a sheet of soft leather, padding mounted over one side of the leather, 85 pockets formed on the upper half of the other side of the leather, curved reinforcing vertical fiber strips disposed within the pockets having their concave sides toward the leather sheet, and a flat sponge rubber 90 pad mounted on the lower half of the second mentioned side of the leather sheet.

3. In a device of the class described the combination of a sheet of soft leather, padding mounted over one side of the leather, 95 pockets formed on the upper half of the other side of the leather, curved reinforcing vertical fiber strips disposed within the pockets having their concave sides toward the leather sheet, a flat sponge rubber pad 100 mounted on the lower half of the second mentioned side of the leather sheet, and eyelets mounted on the leather sheet thru which a lacing medium may be inserted to removably mount the leather sheet upon a 105 garment.

In testimony whereof, I have hereunto 110 subscribed my name this 22nd day of March, 1922.

HUGO GOLDSMITH.
